UNITED STATES PATENT OFFICE.

WILLIAM V. D. KELLEY, OF NEWARK, NEW JERSEY.

GAS-BURNER.

No. 872,350.

Specification of Letters Patent.

Patented Dec. 3, 1907.

Application filed June 3, 1907. Serial No. 376,908.

To all whom it may concern:

Be it known that I, WILLIAM V. D. KELLEY, a citizen of the United States, residing at Newark, in the county of Essex and State 5 of New Jersey, have invented certain new and useful Improvements in Gas-Burners, of which the following is a full, clear, and exact specification.

This invention relates to gas burners, and 10 more particularly has reference to a thermostatically actuated gas burner wherein the gas is automatically turned off and on in order to periodically illuminate a sign or other transparency, or in other relations 15 where it is desired to periodically vary the heat or light derived from a gas flame.

More especially, the present invention is intended to periodically operate a gas burner used for illuminating a sign adapted to be 20 used in places where it is impracticable or undesirable to use electricity.

According to this invention, I have provided a gas burner with a cock connected to be controlled by a thermostat in such manner 25 that the contraction and expansion of the thermostat operates the cock to vary the flow of gas, and consequently the light and heat given out by the burning gas. In combination with the thermostatically controlled 30 gas cock, is a magnetic or other retarding device, acting to prolong one or both of the periods so that the gas switch will not be actuated at too rapid a rate.

The invention will be more fully described 35 in connection with the accompanying drawing, wherein

Figure 1 is a side view of a gas burner embodying the invention; Fig. 2 is a rear view; Fig. 3 is a front view; Fig. 4 is a top plan 40 view; and Fig. 5 is a perspective view showing a complete apparatus.

1 represents a supply pipe having a burning tip 2, and a controlling cock 3 having a gas passage 4 therethrough, so that the flow of 45 gas is determined according to the position of the cock 3. In one position, a full flow of gas is permitted, and in the other position only sufficient flow of gas is permitted to keep the flame lighted. In addition to this 50 automatic cock, the supply pipe 1 will be provided with a hand cock in order to completely cut off the flow when the device is not in operation.

In order to operate the cock 3, a thermo- 55 stat 6 preferably composed of two strips of dissimilar metals, is provided. The thermo-

stat 6 is secured to a support 7 carried by the pipe 1, and is curved upwardly and then downwardly to provide the free end 8 which operates the cock 3. The curved portion of 60 the thermostat 6 is positioned so as to extend preferably into the blue portion of the ordinary illuminating gas flame and be heated thereby when the gas is flowing at full pressure through the cock 3. In order to operate 65 the cock, it is provided with two pins 9, eccentric to its axis of rotation, between which pins the free end of the thermostat 6 engages so that the cock will be oscillated in one direction by the expansion of the thermostat to cut off the flow of gas, and in the other direction by the contraction of the thermostat to turn on the gas.

The thermostat 6 is preferably composed of an outside strip of iron and an inside strip of 75 brass, and when heated, by reason of the greater expansion of the iron, the free end 8 will be thrown to the left in Fig. 1, cutting off the flow of gas and thereby reducing the 80 flame so that the thermostat will cool off and again open the cock by moving it towards the right in Fig. 1. Such a device will operate satisfactorily, but for certain uses, more particularly for illuminating transparencies or signs used in advertising, it is desirable to 85 have the periods of a certain duration, and also to have the transition period from light to dark or dark to light as short as possible. It is especially desirable that the heat be quickly cut off after the diminution of the 90 gas actually commences, and to this end the free end of the thermostat vibrates between the pole of a permanent magnet 10, which latter will attract the thermostat by reason of its being made of magnetic material. If 95 not made of magnetic material, it should be provided with an armature of magnetic material. The operation of the magnet is to hold the thermostat against movement, until the power of the thermostat overcomes the 100 pull of the magnet, whereupon the thermostat snaps quickly over and quickly reduces the flow of gas, so that the flame immediately dies down instead of going down slowly as it would do if the thermostat did not snap over. When the thermostat cools, and thereby turns the gas on it will start to move towards the magnet, and will move more and more quickly as it gets closer to the magnet, 105 so that the opening of the gas cock will be accelerated as well as the closing.

In order to hold the conical cock 3 in its seat

a small spring 12 bearing against a head 13 is provided, and this spring may be mounted on the magnet itself or elsewhere so as to exert a slight tension on the cock 3, but not enough to prevent it from turning easily.

Preferably, in making up the invention, it will be all mounted on the brass burner tube usually found in gas burners and capable of being attached to the extended service pipes 10 or chandeliers to be found almost everywhere.

It will be seen that when the gas flame is cut down a draft of air might blow it out, and to prevent this, a globe 15 is provided 15 which may carry lettering or advertising as well, and thus be periodically lighted and dimmed as the thermostat automatically operates.

It will be seen that one cock 3 could control a number of burners with a single light or burner to constitute a pilot light which would be varied periodically as the thermostat operated the cock, and I do not restrict the invention to using the burner 2, as the 25 lighting burner, because this could be solely to regulate the thermostat and other burners not necessary to be shown, used for flashing the sign or signs.

The particular construction herein shown 30 and described is capable of various modifications and changes without departing from the scope of the invention which is not to be restricted to any particular construction and arrangement.

Having thus described my invention, I declare that what I claim as new and desire to secure by Letters Patent is,—

1. The combination with a gas-burner, of

a thermostat disposed in proximity thereto to be heated by the flame, a gas controlling 40 cock, a mechanical connection between said cock and said thermostat for actuating the cock as the thermostat expands and contracts, a magnet, and a vibratory armature disposed in the field of the magnet and connected to be vibrated by the expansion and contraction of the thermostat, as set forth.

2. The combination with a gas-burner, of a thermostat disposed in proximity thereto and having one portion heated by the flame 50 and another portion movable in response to the expansion and contraction of the heated portion, a regulating cock arranged to vary the flow of gas, an actuating connection between the movable portion of the thermostat and the cock, a permanent magnet, and a movable armature carried by the movable portion of the thermostat and disposed between the poles of the magnet, as set forth.

3. The combination with a gas-burner tube, of a bent thermostat mounted thereon to be heated by the flame and having a free depending end, a cock in said tube adapted to vary the flow of gas without completely cutting off and engaged by said thermostat to be actuated thereby, and a permanent magnet mounted on said tube and having its poles located on opposite sides of said depending portion of the thermostat.

In testimony whereof I affix my signature, in presence of two witnesses.

WILLIAM V. D. KELLEY.
